DEVICE FOR APPLYING GRANULAR MATERIALS

Orlando D. Shonnard, Upper Montclair, N. J., assignor to Joseph Dixon Crucible Company, Jersey City, N. J., a corporation of New Jersey

Application January 14, 1937, Serial No. 120,547

9 Claims. (Cl. 221—32)

The invention relates to an improvement in devices for applying granular materials to surfaces, and more especially to devices for applying finely divided materials, such as powdered graphite, plumbago, and the like, to surfaces to be lubricated or protected from the action of the atmosphere and other deleterious action. More particularly the invention relates to an improvement in such devices provided with means for opening and shutting the nozzle.

It has been proposed heretofore to provide nozzle controlled devices for expelling finely divided materials, in the form of a small cloud, as to surfaces requiring lubrication or protection, and several such devices, some of them patented, have appeared on the market. Although the attempt has been made to satisfy the demand for such devices, especially those for applying powdered graphite, the devices which have heretofore appeared have not been entirely satisfactory for all uses, since their construction has involved expenses requiring a retail price beyond that of many purchasers. Hence, there has arisen a demand for a device of this character which can be produced at low cost and so sold to the trade unable to purchase the more elaborately constructed devices for applying finely divided materials.

One object of the present invention is to produce an improved and simplified device for expelling from a reservoir finely divided material when needed, such as powdered graphite or the like to surfaces requiring lubrication, or protection from the action of the atmosphere or the action of other natural elements. A further object of the invention is to produce a device of this character of such construction that it can be manufactured cheaply and so be sold at retail at prices within the range of the purchasing power of large numbers of persons who cannot afford to purchase the more expensive and elaborate devices of this nature heretofore placed on the market. Another object of the invention is to provide such devices with improved means for controlling the expulsion of the powdered material. Another object of the invention is to produce a device of this character having provision for ready removal of the nozzle assembly for refilling and cleaning purposes, should those occasions arise. To these ends the invention consists in the improved device for applying finely divided materials hereinafter more fully described and particularly pointed out in the appended claims.

In the accompanying drawing illustrating the preferred form of the invention, Fig. 1 is a side

elevation of the improved device for applying granular materials, with the nozzle turned to open position; Fig. 2 is a view of the upper part of the device shown in Fig. 1, but with the nozzle turned to closed or shut position; Fig. 3 is a top plan of the device shown in Fig. 1; Fig. 4 is a longitudinal section, on an enlarged scale, taken on the line 4—4 of Fig. 1, and showing the nozzle in open position; Fig. 5 is a view similar to Fig. 4, but with the nozzle in closed position; Fig. 6 is a transverse section taken on the line 6—6 of Fig. 4; and Figs. 7, 8 and 9 are views, similar to Fig. 4, of modified forms of the invention.

The improved device for expressing and applying finely divided materials, such as applying powdered graphite or other granular materials to surfaces, as illustrated in the drawing, comprises an elongated resilient cylindrical reservoir 10, which may conveniently be composed of any resilient material, such as celluloid, closed at its inner or lower end 11 and open at its outer or upper end 12. In the open end 12 of the cylindrical resilient reservoir 10 is located a plug or stopper 14 composed of a resilient material, such as cork. The resilient plug 14 has a smooth cylindrical exterior to fit tightly in the outer end of the reservoir, and flat inner and outer faces. The plug 14 may be permanently secured in the open end of the reservoir 10, as by cementing, or it may be tightly but removably located therein, being secured against accidental removal therefrom by any convenient means such as the nail 13.

In the preferred form of the invention illustrated in Figs. 1 to 6, the plug 14 is provided axially throughout its length with a cylindrical bore adapted to receive snugly but rotatably the tubular inner part or extension 15 of a nozzle assembly consisting of the conical tubular nozzle proper 17 provided at its inner end with a disk-like collar 16 having a flat inner face adapted to seat against the outer end of the reservoir 10 and adjacent to the outer face of plug 14, as shown in Figs. 4 and 5. From the center of the collar 16 the conical tubular nozzle 17 extends outwardly, having a contracted orifice 19 in its outer end. The inwardly extending portion 15 of the nozzle assembly constitutes an inner prolongation of the nozzle 17. The disk-like collar 16 is provided at its outer edge with a rearwardly extending annular flange 18 which snugly but rotatably embraces the exterior surface of the outer end of the reservoir 10 so that the nozzle structure as a whole, composed of the parts 15, 16, 17 and 18, may be rotated.

It has been found desirable in the operation of devices like that of the present invention, for expressing from a container or reservoir finely divided materials, such as powdered graphite, to 5 provide means for preventing the expulsion of the material except when needed. To this end the device of the present invention is provided with novel means for permitting the expression of the finely divided material 20 from the reservoir 10 only when needed, and for preventing the accidental expulsion of the material from the device when it is not in operation: The inner end of the tubular portion 15 of the nozzle, which is wholly received within the central 10 bore of the resilient plug 14, is closed by a cap 21 of not larger diameter than the part 15, and is provided laterally near its inner extremity with a small hole or aperture 22 (of substantially the same size as the orifice 19) which when the 15 device is to be used opens into a recess or bore 24, which serves as an auxiliary reservoir, formed in the inner end of the plug 14 and opening into the cylindrical bore in the plug in which the part 15 of the nozzle is located. The internal 20 diameters of the inner nozzle part 15 and the bore or recess 24 are substantially the same. When the nozzle is in this position, with the hole 22 opening into the recess 24, an arrow 25 located on the sloping outer surface 26 of the 25 collar 16, is in registry with a mark or line 21 on the exterior surface of the outer end of the reservoir 10, the mark 27 being designated by the legend "Open".

It is desirable to permit only a predetermined 30 amount of finely divided material 20 to be expelled at one operation of the device to pass into the recess 24 from the reservoir. For this purpose a plate 28 secured against the lower or inner face of the plug 14 is provided with a hole 35 29 (of substantially the same size as or smaller than the hole 22), which permits only restricted quantities of the material 20 to pass into the recess 24 when the resilient sides of the reservoir are squeezed, thereby preventing clogging of the 40 ducts of the device. From the recess 24 the granular material passes out through the aperture 22 and the orifice 19.

Plate 28 is preferably of a stiff, compression 45 resistant material, such as fiber or metal, having an external diameter slightly less than the internal diameter of the cylindrical reservoir 10. At its central point the plate 28 is perforated to receive the inner extremity of the nozzle part 15. The plate 28 may be secured to the inner face of the 50 resilient plug 14 by any convenient means, as by cementing, or by the nails 30. It is well known that although cork is resilient, and may be easily compressed, it does not tend readily to return to its former size or position, and that 55 after repeated compressions it is appreciably smaller than its original size. In order to prevent the inner end of the resilient plug 14, which is conveniently composed of cork, from being compressed into a permanently less size than its original diameter, the present invention provides at the end or face of the plug 14, the plate 28 which resists the inward compression of the outer end of the reservoir 10, when the middle portion thereof is squeezed to express the finely 60 divided material from the reservoir. In this manner the original size of the resilient plug 14 is preserved and it continues to fit tightly in the open end of the reservoir throughout the active 65 service of the device.

70 By rotating the nozzle structure in either di-

rection, the hole 22 is moved away from alignment with the recess 24 and is brought against the wall of the central bore in the plug 14, whereby egress of material from the device is prevented, since the tubular part 15 of the nozzle is snugly engaged by the central cylindrical bore in the resilient plug. Although the recess 24 is conveniently a cylindrical bore in the inner end of the plug 14, and so extends only a short distance around the circumference of the cylindrical inner end 15 of the nozzle, the "Shut" position of the nozzle is conveniently indicated on the opposite side of the cylindrical reservoir 10, as indicated at 32 in Fig. 2.

In the modified form of the invention shown 15 in Fig. 7 the tubular inner portion 34 of the nozzle 36, corresponding to the tubular inner portion 15 of the nozzle structure of Figs. 1 to 6, terminates within the plug 35 short of the inner face 31 thereof and is closed by a plug 38, 20 which presses snugly against the bottom of the central bore in the plug 35. The finely divided material 20 is expressed from the resilient reservoir 10 out through the orifice 39 of the nozzle 36 by way of the hole 41 in the plug 38, the 25 hole 42 in the inner end of the resilient plug 35 against which the plug 38 seats, and the hole 43 formed in the plate 44 corresponding to the plate 28 in Figs. 4 and 5. The hole 41 is eccentrically located in the plug 38, and is adapted to register 30 in one position of the nozzle 36 with the holes 42 and 43, which are located in stationary parts 35 of the device. Hence, when the nozzle 36 is turned in either direction a short distance the hole 41 is moved out of alignment with the holes 42 and 43, and when it is turned in the reverse direction the proper amount, the hole 41 is again brought into registry with the holes 42 and 43.

In the modified form of the invention shown 40 in Fig. 8, the inner tubular portion 45 of the 45 nozzle 46 is provided with a cup-shaped sealing plug 47 having a lateral flange 48 which overlies not only the inner end of the tubular portion 45 of the nozzle but also the adjacent inner part 49 of the plate 50, which construction prevents the removal of the nozzle 46 from the device unless the fastening means such as the nail 52 for preventing accidental removal of the plug 53 from the outer end of the reservoir 10 is first taken out. The plate 50 shown in Fig. 8 50 may conveniently be held against the inner face of the plug 43 by the teeth 55 turned outwardly from the plate itself. In respects other than those described above, the form of the invention shown in Fig. 8, is similar to that shown in Figs. 4 and 5. It will be understood that the nozzle assembly shown in Fig. 8 constitutes with the resilient plug 53 a unitary structure for removal from and reinsertion in the open end of the reservoir.

The device of the present invention for applying finely divided materials on surfaces, because of its simplicity of construction and consequent low selling price, justifies its cost when the material, such as powdered graphite, contained 65 within the reservoir 10 is used up. The empty device can then be thrown away. With the more frugally minded, however, there is a demand for refillable devices. Those illustrated in Figs. 1 to 8 may all be refilled by removing the means 70 holding the resilient plug in the open end of the reservoir and then by one means or another abstracting the sealing plug. However, these forms of the invention are not particularly adapted for ready removal of the sealing plug from 75

the reservoir. A more convenient means of removing the sealing plug for refilling the reservoir is shown in the modified form of the invention illustrated in Fig. 9, which is substantially the same in construction and mode of operation as the form of the invention shown in Figs. 1 to 3, except that the resilient sealing plug 57 is shown provided with an outwardly extending part 64 the outside diameter of which is substantially the same as the outside diameter of the cylindrical reservoir 10, and is provided with a shoulder 59 which seats against the outer open end of the reservoir 10. In this form of the invention the slightly conical collar 60 of the nozzle 61 terminates at its outer edge 63 flush with the periphery of the outer end 64 of the resilient plug 57, thereby providing an area which may be grasped by the fingers of the user and so be readily pulled out of the reservoir 10, after removing the fastening means, such as the nail 65, which holds the resilient plug 57 against accidental displacement from the reservoir 10. In this connection, it will be understood that the cooperation of the resilient materials of which the reservoir and sealing plug are composed hold the plug tightly in the reservoir, and that the auxiliary fastening means, such as the nails shown in the various modifications of the invention are only provided to secure against accidental removal of the plugs. It will be understood further that in those cases in which the resilient sealing plug is not to be removed from the reservoir, it may be permanently secured therein, as by means of cement or the like without the use of mechanical fastening means.

Whether the resilient sealing plugs are permanently or removably secured in the reservoirs, the nozzles may or may not be permanently connected with the sealing plugs. The nozzle assemblies shown in Figs. 4, 5, 7 and 9 provide a convenient arrangement for the ready removal of the nozzle assembly only, without the plug, in case it should be desired to clean out the ducts of the nozzle.

Having thus described the invention, what I claim as new is:—

1. A device for applying granular materials to surfaces comprising, a cylindrical reservoir for containing the granular material, said reservoir being composed of resilient material whereby when its sides are compressed the granular material is expressed from the reservoir, said reservoir having a closed end and an open end, a resilient plug closing the open end of the reservoir and having a central bore, and a nozzle structure having a collar adapted to lie adjacent the outer end of the resilient plug, a tubular nozzle extending outwardly from the center of the collar, and a tubular inner portion with a closed inner end extending inwardly from the collar and constituting a prolongation of the nozzle, said inner portion of the nozzle being received within the central bore in the resilient plug, said nozzle structure being rotatable in the resilient plug and having an open position and a shut position, said inner tubular portion of the nozzle having a relatively small hole adapted to be closed by the plug when the nozzle structure is turned to shut position, and the inner end of the resilient plug having a hole of substantially the same size as the hole in the inner tubular portion of the nozzle, said hole in the nozzle portion being arranged to communicate with the hole in the plug when the nozzle structure is turned to open position.

2. A device for applying granular materials to surfaces comprising, a reservoir for containing the granular material, said reservoir being composed of resilient material whereby when its sides are compressed the granular material is expressed from the reservoir, said reservoir having a closed end and an open end, a resilient plug closing the open end of the reservoir and having a central bore, and a nozzle structure having an outwardly extending tubular nozzle and an inwardly extending tubular portion with a closed inner end received within the central bore of the resilient plug, said nozzle structure being rotatable in the plug and having an open position and a shut position, said inner tubular portion of said nozzle and the inner end of the resilient plug having holes arranged to communicate with each other when the nozzle is turned to open position, and the hole in the inner tubular portion of the nozzle being closed by the resilient plug when the nozzle is turned to shut position.

3. A device for applying granular material to surfaces, comprising a reservoir for containing the granular material, said reservoir being composed of celluloid and having a closed end and an open end, a resilient plug inserted in the open end of the reservoir and having a central bore extending throughout its length, and a rotatable nozzle structure mounted in the plug and consisting of a collar enclosing the open end of the reservoir and the plug, a tubular nozzle extending outwardly from the collar and a tubular inner portion extending inwardly from the collar rotatably received in the bore in the plug and constituting a prolongation of the nozzle, means of not greater diameter than the inner part of the nozzle for closing said inner portion of the nozzle, said nozzle structure being rotatable and having open and shut positions, said inwardly extending portion of the nozzle and the inner end of the resilient plug having holes adapted to communicate when the nozzle is in open position, whereby the granular material in the reservoir may be expressed through the nozzle when the sides of the reservoir are forced inwardly, and said hole in the inner portion of the nozzle structure being closed by the resilient plug when the nozzle structure is turned to shut position.

4. A device for applying granular materials to surfaces comprising, a reservoir for containing the granular material, said reservoir being composed of resilient material and having a closed end and an open end, a resilient plug closing the open end of the reservoir, said resilient plug having a central cylindrical bore, a rotatable nozzle structure mounted on the open end of the reservoir and consisting of a tubular conical nozzle having an orifice at its outer end, a collar having a flat inner surface adjacent the outer end of the resilient plug and resting on the open outer end of the reservoir, and a tubular portion with a closed inner end constituting a prolongation of the nozzle and extending inwardly from the collar and being received in the central bore of the resilient plug, the inner end of the tubular portion of said nozzle having a hole offset from its axis, and the inner end of the resilient plug having a hole leading from the reservoir and being of substantially the same size as the offset hole in the tubular inner end of the nozzle, said holes being adapted to register with one another when the nozzle is turned to one certain position, said holes being of substantially the same size as the orifice of the nozzle.

5. A device for applying granular materials to

surfaces comprising, an elongated reservoir for containing the granular material, said reservoir being composed of resilient material and having a closed end and an open end, a resilient plug 5 having a central bore inserted in the open end of the reservoir, a nozzle structure consisting of a tubular outwardly extending nozzle having an orifice in its outer end, and a tubular portion with a closed inner end extending inwardly from the 10 nozzle constituting a prolongation of the nozzle and being received within the central bore of the resilient plug, said nozzle structure being rotatable and having an open and a shut position, and a plate of substantially incompressible material 15 and of substantially the same diameter as the plug secured to the inner face of the plug, said inwardly projecting portion of the nozzle and the plate having holes adapted to communicate when the nozzle structure is in open position, said hole 20 in the nozzle being closed by a portion of the resilient plug when the nozzle structure is turned to shut position.

6. A device for applying granular materials comprising, a cylindrical resilient reservoir for 25 containing the granular material, said reservoir being closed at one end and open at the other, a resilient cylindrical plug with a smooth exterior inserted tightly in the open end of the reservoir, said plug having a central cylindrical bore, 30 a metal plate of substantially the same diameter as the plug secured to the inner end of the plug, a rotatable nozzle structure consisting of a disk-like collar having a flat inner surface and a backwardly extending annular flange adapted to 35 brace the open end of the reservoir, a conical tubular nozzle extending outwardly from the center of the collar and having an orifice in its outer end, and an inwardly extending tubular portion received within the central bore of the plug, 40 means for closing the inner end of the inner portion of the nozzle, said closing means being not larger in diameter than the inner portion of the nozzle, said plug having in its inner end a recess opening into the reservoir, said plate having 45 a hole opposite the recess, said inner portion of the nozzle having a lateral hole adapted to register with the recess when the nozzle structure is rotated, said holes and the orifice of the nozzle being of substantially the same size and substantially 50 smaller than the recess and the internal diameter of the inner portion of the nozzle.

7. A device for expressing granular materials comprising a resilient reservoir having a closed end and an open end, a plug secured in the open 55 end of the reservoir and having an axial bore

throughout its length, a nozzle rotatably mounted in the bore of the plug, means for closing the inner end of the nozzle, said means cooperating with the inner end of the plug to prevent the removal of the nozzle from the plug, said nozzle and said plug having apertures adapted to communicate when the nozzle is in a certain position. 5

8. A device for applying granular materials to surfaces comprising, a reservoir for containing the granular material, said reservoir being composed of resilient material whereby when its sides are compressed the granular material is expressed from the reservoir, said reservoir having a closed end and an open end, a plug closing 10 the open end of the reservoir and having a central bore, a nozzle structure having an outwardly extending tubular nozzle and an inwardly extending tubular portion with a closed inner end received within the central bore of the plug, said 15 nozzle structure being rotatable in the plug and having an open position and a shut position, said inwardly extending tubular portion of the nozzle and the inner end of the plug having holes arranged to communicate with each other when the nozzle is turned to open position, and the hole in the inwardly extending tubular portion of the 20 nozzle being closed by the plug when the nozzle is turned to shut position.

9. A device for applying granular materials to 25 surfaces comprising, a reservoir for containing the granular material, said reservoir being composed of resilient material whereby when its sides are compressed the granular material is expressed from the reservoir, said reservoir having a closed end and an open end, a plug closing the 30 open end of the reservoir and having a central bore, and a nozzle structure having an outwardly extending tubular nozzle and an inwardly extending tubular portion with a closed inner end received within the central bore of the plug, said 35 nozzle structure being rotatable in the plug and having an open position and a shut position, and a plate secured to the inner end of the plug and being of substantially the same contour as the inner surface of the reservoir so as to fit snugly 40 therein, said inner tubular portion of said nozzle structure and the plate on the inner end of the plug having holes arranged to communicate with each other when the nozzle is turned to open 45 position, and the hole in the inner portion of the tubular extension of the nozzle structure being closed by the plug when the nozzle is turned to shut position. 50

ORLANDO D. SHONNARD.
